[57] CLAIM

The ornamental design for air intake control valve member for swimming pools and spas, as shown and described.

DESCRIPTION

FIG. 1 is a side elevational view of an air intake control valve member for swimming pools and spas showing my new design;

FIG. 2 is top plan view thereof;

FIG. 3 is a bottom plan view thereof; and

FIG. 4 is a cross sectional view thereof taken on line 4—4 of FIG. 2.

FIG. 1.

FIG. 2.

FIG. 3.

FIG. 4.
